UNITED STATES PATENT OFFICE.

THOMAS P. POMEROY, OF FREEPORT, MICHIGAN.

OXYGEN INFLATING DEVICE.

SPECIFICATION forming part of Letters Patent No. 792,348, dated June 13, 1905.

Application filed December 19, 1904. Serial No. 237,561.

To all whom it may concern:

Be it known that I, THOMAS P. POMEROY, a citizen of the United States, residing at Freeport, in the county of Barry and State of Michigan, have invented a new and useful Oxygen Inflating Device, of which the following is a specification.

This invention relates to devices for supplying gaseous or semigaseous bodies to affected parts medicinally, more particularly for use in veterinary practice, and has for its object to produce a simply-constructed and efficacious device of this class, whereby the gaseous body may be supplied under any desired pressure and purified and sterilized and antiseptically treated before discharge from the device.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, there is illustrated a preferred form of the embodiment of the invention capable of carrying the same into practical operation, it being understood that the invention is not necessarily limited thereto, as various changes in the shape, proportions, and general assemblage of the parts may be resorted to without departing from its principle or sacrificing any of its advantages.

In the accompanying drawings, Figure 1 is a sectional side elevation of the improved device. Fig. 2 is a transverse section on the line 2-2 of Fig. 1 with the cover of the receiver removed.

This device is employed to transmit a gaseous body under pressure, and is more particularly designed for use in veterinary practice, and especially for treating parturient apoplexy, or what is generally known as "milk-fever," in cows or other diseases of the udder; but while the device is more particularly applicable to the treatment of diseases of this character it will be understood that the invention is not to be limited thereto, as it

may be effectually employed for many other purposes.

The improved device comprises a receiver 10, having a detachable mouthpiece 11 preferably threaded thereon, and provided with a detachable closure 12, preferably threaded upon the mouthpiece. Disposed within the receiver 10 is a tubular member 13, entering the receiver at one side near the bottom and provided with means, such as a threaded sleeve 14, for attachment to an air-pump 15, as by a threaded nipple 16 on the pump, there being a valve 16^a provided in the nipple to prevent the air that has been forced through the member 13 from returning during the upward stroke of the piston. This valve may be of the usual or any preferred construction, and therefore needs no detailed description. The upper portion of the receiver 10 is coupled to the pump by an inclosing band 17 and clamped in position by a transverse bolt 18 and its nut 19. The pump is preferably provided with a foot loop or rest 20 to enable the operator to hold the pump steady while operating the plunger-rod 21.

The upper end of the tubular member 13 is enlarged into a chamber 22 and provided with a perforated closure 23, preferably threaded upon the chamber for ready removal from or attachment thereto, and provided with a stem or stud 24, accessible through the mouthpiece 11, so that the closure 23 may be readily removed from or attached to the chamber through the mouthpiece. The chamber 22 is designed to hold a sponge, medicated cotton, or similar material 25 for charging with antiseptic or other material or compound, and to support the sponge or like material the bottom of the chamber is provided with transverse-spaced wires 26, or a section of wire-netting may be employed for this purpose, if preferred. An additional mass of sponge, cotton, or the like material may be placed within the space between the chamber-closures 12 and 23, as indicated at 27, if found necessary or desirable.

Connected, as by a threaded nipple 28, to the bottom of the receiver is a discharge-conduit 29, preferably of flexible material, such

as rubber hose or the like, and terminating in a tubular member 30, having perforations 31 at the outer end. The member 30 will be small enough to be thrust through milk-ducts 5 in the teats of a cow and into the udder when the device is employed for treating parturient apoplexy and like diseases and will be detachable from the conductor member, as by a threaded nipple 32, to permit instruments of 10 other forms to be substituted when required.

With an apparatus such as described it is obvious that a gaseous body may be caused to pass under pressure through the receiver 10 and discharged from the relatively small 15 apertures 31 in the outlet end of the member 30 and also caused to pass through the intercepting sponges or like material 25 to 27 and be thereby antiseptically or otherwise treated or charged. Ordinarily the gaseous body 20 passed through the device will be the common atmosphere and denuded of all impurities by the compound, such as carbolic acid or the like, carried by the intercepting sponges or other material, so that only the purified 25 air finds its way from member 30 when the oxygen therein will be in proper condition to perform the requisite remedial effects. The gaseous body thus treated may be subjected to any desired degree of pressure and 30 discharged from the member 30 with any desired degree of force and inflate the udders of cows to any desired extent when the device is employed in the treatment of such parts or organs.

35 The parts are all readily detachable for cleansing or renewal, and the device can be inexpensively manufactured and will be very durable and efficient in operation. The sponges or other like members 25 to 27 may be 40 quickly removed for recharging or renewal and as readily reinserted, as will be obvious.

Having thus described the invention, what is claimed is—

1. An apparatus of the class described 45 comprising a receiver, a tubular member arranged therein and carrying a chamber disposed near one end of the receiver to contain

an antisepticized material, a conduit communicating with the other end of the receiver and terminating in a nozzle, and means connecting with the tubular member for forcing aeriform fluid under pressure therethrough. 50

2. An apparatus of the class described comprising a receiver, a detachable closure combined with one end thereof, a tubular member arranged within the receiver and provided with a chamber disposed near one end of the receiver to contain an antisepticized material, a perforated cap detachably connected with the chamber and provided 55 with a stem disposed within the mouth of the receiver, means for supplying an aeriform fluid under pressure through the tubular member and the chamber, and means for conducting such fluid from the receiver. 60

3. An apparatus of the class described comprising a receiver, a tubular member disposed therein and provided at one end with a chamber containing an antisepticized material, the intake end of the member being furnished with a threaded sleeve, an air-pump having a threaded extension engaging the sleeve, a conduit communicating with the receiver and terminating in a laterally-discharging nozzle, and a band encircling the 70 pump and the receiver and provided with means to secure it in position around the parts. 75

4. In an apparatus of the class described, a receiver, a tubular member therein provided 80 at its upper end with a chamber, means communicating with the tube for supplying an aeriform fluid under pressure thereto, a perforated closure for the chamber, and a conduit communicating with the receiver near its 85 lower end and terminating in a nozzle.

In testimony that I claim the foregoing as my own I have hereto affixed my signature in the presence of two witnesses.

THOMAS P. POMEROY.
